L. F. Mustee.

UNITED STATES PATENT OFFICE.

LAWRENCE FRANK MUSTEE, OF CLEVELAND, OHIO.

OIL-BURNER.

No. 849,259.

Specification of Letters Patent.

Patented April 2, 1907.

Application filed July 9, 1906. Serial No. 325,839.

To all whom it may concern:

Be it known that I, LAWRENCE FRANK MUSTEE, a citizen of the United States, residing at Cleveland, in the county of Cuyahoga and State of Ohio, have invented certain new and useful Improvements in Oil-Burners; and I do declare the following to be a full, clear, and exact description of the invention, such as will enable others skilled in the art to which it appertains to make and use the same.

This invention relates to improvements in oil-burners, and consists in the novel construction, combination, and arrangement of devices hereinafter described and claimed.

The object of the invention is to improve the construction and operation of devices of this character and thereby render the same more efficient and durable and less expensive.

The above and other objects, which will appear as the nature of my invention is better understood, are accomplished by means of the construction illustrated in the accompanying drawings, in which—

Figure 1 is a front elevation of the improved oil-burner, parts being broken away to more clearly illustrate the construction. Fig. 2 is a vertical sectional view through the same. Fig. 3 is a detail sectional view taken on the plane indicated by the line 3-3 in Fig. 1. Fig. 4 is a perspective view of one of the braces or brackets for supporting the air-draft ring or collar and the drum, and Fig. 5 is a similar view of the spring for holding the wick in its carrier.

The embodiment of the invention shown in the drawings is in the form of an oil-burner adapted for use on a stove and having a body or reservoir 1, to which oil is supplied from a tank or other source of supply through a supply-pipe 2. The reservoir or oil-receptacle 1 is in the form of a hollow cylinder having inner and outer walls 3, 4 connected at their bottoms to provide a space 5 for the oil. The inner cylinder or wall 3 has around its top an inwardly-extending annular shoulder 6 for the reception of the flattened upper end of a circular wick 7, which latter extends downwardly into the oil-space 5 between the two walls 3, 4 and contacts with the inner wall 3. This wick is connected to and raised and lowered by means of a carrier 8, which is in the form of a cylinder provided with rows of perforations 9 and having adjacent to its bottom upon its inner face inwardly-pro-

jecting spurs 10 to enter the wick. The latter is held in engagement with said spurs by a split circular spring 11, which surrounds the inner wall 3, as seen in Fig. 2. The cylindrical wick-carrier 8 slides vertically in the oil-space 5 and is guided by its engagement with the inner face of the reduced upper portion 12 of the outer wall 4.

The wick is raised and lowered by turning a hand-wheel 13, secured upon the outer end of a downwardly-inclined shaft 14, mounted for rotation in a tubular bearing 15, which projects into a casing 16, secured upon the outer face of the wall 4 of the body 1. Fixed upon the shaft 14 within the casing or jacket 16 are two toothed wheels 17, which engage the apertures 9 in the wick-carrier 8, and thereby raise or lower the latter when the hand-wheel 13 is rotated.

Within the inner wall or cylinder 3 is an annular perforated ring 18, formed with a depending flange 19, which is secured to the wall 3, and with an upwardly-projecting annular flange 20, adapted to be engaged by the lower end of a perforated air-spreader cone 21. Secured upon the top of this cone by a rivet or the like 22 is a circular flame and air-spreader plate 23. The latter is dished with its concave side lowermost and extends over the flattened upper end of the wick 7, as clearly shown in Fig. 2.

Engaged with an annular shoulder 24, formed by reducing the diameter of the upper portion of the outer wall 4 of the body 1, are a series of spacing and supporting brackets 25, each of which is formed from a single piece of heavy sheet metal by cutting and bending the same to provide a substantially U-shaped body, which has at its top an outwardly-extending tongue 26. This U-shaped body of the bracket has its parallel ends or arms 27 projecting angularly from its connecting portion 28 and shaped to engage the shoulder 24, and upon the outer face of the connecting portion 28 is secured by a rivet or the like 29 an annular collar or sleeve 30. The collar or ring 30 is thus supported by and spaced from the reduced upper end 12 of the outer wall 4 of the lamp-body, so as to provide an annular space 31 for the passage of air. The upper edge of the ring or collar 30 is slightly inturned and terminates slightly above the portion 12 of the wall 4, as clearly shown in Fig. 2. The tongues 26 of the brackets or braces 25 project through apertures formed in the ring or collar 30 and are

adapted to support the corrugated annular ring or flange 32 upon a cylindrical drum 33. This drum has at its top a similar corrugated flange or ring 34, which extends inwardly and 5 reduces the opening in the top of said drum. The corrugated flange 32 is provided at the bottom of the drum, so as to provide openings or spaces for the inlet of air into the drum around the outer side of the ring or collar 30. 10 At a suitable point in the vertical wall of the drum 33 is formed an opening adapted to be closed by a door 35, hingedly mounted, as at 36, and provided with mica, so as to permit the flame of the burner to be seen from without the drum. 15

The oil-receptacle or reservoir 1 is adjustably connected to the supply-pipe 2 by providing upon the former an oil-inlet nipple or connection 38, adapted to receive one end of 20 a coupling 39, which has its outer end secured in the pipe 2. The coupling 39 is formed with an annular flange 40 to engage the outer edge of the connection 38, and a lead washer or the like 31' is placed between the latter 25 and the coupling 39, as shown in Fig. 2. The coupling is held firmly against the connection 38 by a strap or band 42, which is passed over the pipe 2 and has its apertured ends engaged with lugs 43, formed at opposite points 30 on the connection 38. Provided in the outer portion of the band 42 is a nut 44 to receive a set-screw 45, which has its inner end impinging against the pipe 2. It will be seen that when said screw 45 is screwed into the nut 35 the ends of the band 42 will be drawn upon to draw the connection 38 into the coupling 39 and tightly against the washer 41.

The operation and advantages of the burner will be readily understood. It will be 40 seen that the annular shoulder 6 at the top of the inner wall of tube 3 will keep the oil from running down the inside of the latter and cause the condensed oil to be burned. It will also prevent the wick from burning unevenly and prevent the air-draft from cutting 45 the flame from the wick. The necessary

amount of air is fed to the flame at the top of the wick through the perforations in the ring and cone 21, and the deflector 23 will direct it, so that the proper combustion is secured. 50 The drum 33 produces a draft through the space 31 and the corrugated portion 32 at its bottom, so that the necessary amount of air is supplied to the burner.

Having thus described my invention, what 55 I claim as new, and desire to secure by Letters Patent, is—

1. In an oil-burner, inner and outer wick-tubes, the outer tube being shouldered near its upper end, a perforated collar around and 60 at a distance from the upper ends of said tubes, the upper end of said collar being in-turned and extending above the said tubes, substantially U-shaped brackets rigidly secured to said collar, each bracket having its 65 upper end bent laterally and projected through one of the openings in the collar and the lower ends of the brackets resting on said shoulder, and a drum around the collar, the lower end of which is corrugated and bent inward and rests on the projecting ends of said brackets. 70

2. In an oil-burner, inner and outer wick-tubes, a collar around and at a distance from and extending above the upper ends of said tubes, a perforated ring in the inner tube provided with an upward-extending flange at its inner edge and with a depending flange at the outer edge which is secured to said inner tube, a perforated conical air-spreader resting on said ring around said upward-extending flange, and a depending spreader-plate secured to the top of said cone with its edge adjacent to the upper ends of said tubes and collar. 80

In testimony whereof I have hereunto set my hand in presence of two subscribing witnesses.

LAWRENCE FRANK MUSTEE.
